Primary Examiner — Adir Aronovich*Assistant Examiner* — Ethiene Salgado-Rodriguez(74) *Attorney, Agent, or Firm* — Knobbe Martens Olson & Bear LLP(57) **CLAIM**

The ornamental design for a face decoration for a bag, as shown and described.

DESCRIPTION

FIG. 1 is front elevational view of a face decoration for a bag showing our new design as applied on the side of a bag.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof; and,

FIG. 7 is a front elevational view showing a tongue portion of the decoration withdrawn behind two zippers.

The dashed broken lines that appear in FIGS. 1 and 7 depict stitching lines which are part of the claimed design. The dotted broken lines in the figure drawings are included for the purpose of illustrating environment and form no part of the claimed design. The dot-dash broken lines in FIGS. 1 and 7 define the boundary of the claimed design and form no part thereof.

1 Claim, 7 Drawing Sheets(56)
